UNITED STATES PATENT OFFICE.

THOMAS E. GENTHNER AND ADELBERT L. STEVENS, OF BOSTON, MASSACHUSETTS.

MUFFLER.

Application filed September 15, 1920. Serial No. 410,488.

To all whom it may concern:

Be it known that we, THOMAS E. GENTHNER and ADELBERT L. STEVENS, citizens of the United States, and residents of Boston, 5 in the county of Suffolk, in the State of Massachusetts, have jointly invented a certain Improvement in Mufflers, of which the following is a specification, reference being had to the accompanying drawings.

10 This invention relates to mufflers for use with internal combustion engines and more particularly to those used with the engines of motor boats, in which provision is made for the circulation of sea water through the 15 water jacket of the engine; our object being to provide a specially simple and cheap form of muffler which may be readily adjusted to receive the intake and discharge pipe connections.

20 In order to explain our invention clearly we have provided the annexed drawings, in which the Figure 1 is a side elevation of a muffler embodying our present improvements and Figure 2 is mainly a vertical, 25 sectional, view taken at the line 2—2 of Figure 4. Figure 3 is a top or plan view of the complete muffler. Figure 4 is a horizontal, sectional, view taken at the line 4—4 of Figure 1. Figure 5 is an elevation 30 of one of the members of the muffler detached and partially broken away.

Referring to these drawings, the reference numerals 10 and 11 indicate the two companion members of our new muffler, said 35 members being exactly alike as to size and form excepting only that provision is made for locating a suitable gasket or packing between the meeting, flanged, edge portions of the said members; one of said edge portions being rabbetted, as at 12, to receive 40 a gasket 13, the edge portion of the other member being suitably turned down to fit into said rabbet, as is clearly seen at 14 in Figure 2 of the drawings.

45 The member 10 is provided near its upper portion with a circumferential opening and a boss 15 which is adapted to receive a pipe 16 which leads from the engine exhaust, and the member 11 is provided near 50 its lower portion with a like opening and a boss 17 that is adapted to receive a pipe 18 which leads overboard from the muffler. 19 denotes an opening in the dome of member 10 into which is screwed a pipe 20 which 55 leads from the water-jacket of the engine, and 21 denotes an opening in the bottom

of member 11 into which is screwed a water pipe 22 which leads overboard.

When the two described members 10 and 11 are assembled, as seen in Figures 1 and 60 2, they are clamped together by means of a centrally located bolt 23 and nut 24, this construction and relative arrangement of parts being such that, before the nut 24 is screwed home, the members 10 and 11 may 65 be adjusted rotatively, if necessary, in order that the bosses 15 and 17 may be easily lined up with their respective pipes 16 and 18 instead of being compelled to bend or otherwise adjust the pipe ends, as is often necessary when connecting up with the muffler.

The member 10 is formed with a depending, integral, baffle-plate 25 which is of such length that it extends nearly to the bottom of the member 11 when said members are 70 assembled, and the member 11 is formed with a like baffle-plate 26 which extends nearly to the dome of member 10 when said members are assembled (see Figure 2) each baffle-plate being formed of two sections or 75 portions that are at approximately right angles to each other and, when the two members 10 and 11 are assembled the apexes of the said angles are spaced apart in opposition to each other as is best seen in Figure 80 85 4 of the drawings.

When our described muffler is in service the exhaust products are discharged through pipe 16 into the said muffler and impinge against the opposing, inner, face of baffle-plate 25 and then pass down to and under, 90 the lower end of said baffle-plate 25. The exhaust then passes upward, over the top of the baffle-plate 26 and thence downward, and is finally discharged through pipe 18. 95 Meanwhile, the water from the water-jacket enters the muffle through pipe 20 and follows, mainly, the courses taken by the exhaust, as we have just described but, in order that the muffler may not become filled, 100 and congested, by said water, we have provided one or more openings 27 in the baffle-plate through which a considerable portion of the water may find a more direct escape.

It should be noted that, when the exhaust enters the muffle, it is discharged more or less forcibly against the angular walls of the baffle-plate 25 instead of against a flat plate, as is most common in devices of this general type, so far as we are familiar 105 with them. The force of the impact of the incoming exhaust is thus relieved and bro- 110

ken up and the tendency to gradually wear away the baffle-plate is almost entirely overcome, as we have demonstrated by actual use of our muffler.

5 Having thus described our invention, we claim:—

1. A muffler of the class described consisting of two members of substantially like structure adapted to be secured together to form a chamber therebetween; a gas inlet and a water inlet in one of said members; a gas outlet and a water outlet in the other of said members; a baffle plate attached to each of said members adapted to partially divide said chamber; and means to rotatably adjust said members whereby said inlets and outlets may be relatively angularly arranged to align with pipes previously installed and adapted to connect therewith.

20 2. A muffler of the class described consisting of two members of substantially like structure having pivotal connection with a device that normally serves to hold said members in adjusted operative position; a gas inlet and a water inlet in one of said members arranged eccentrically with relation to said pivotal device; a gas outlet and a water outlet in the other of said members also eccentrically arranged with relation to said pivotal device; and a baffle plate attached to each member of greater length than the depth of said member.

3. A muffler of the class described consisting of two members of substantially like structure, having a centrally disposed pivot adapted to firmly secure said members in a desired angular relative position; a chamber formed by the union of said members; a gas inlet and a water inlet in one of said members eccentrically arranged with respect to said pivot; a gas outlet and a water outlet in the other of said members also eccentrically arranged with respect to said pivot; and a baffle plate attached to each of said members so arranged as to divide that

portion of the chamber formed by its member, and extend an appreciable distance into that portion of the chamber formed by the other member.

4. A muffler of the class described consisting of two members of substantially like structure, having a centrally disposed pivot adapted to normally firmly secure said members in a desired angular relative position; a gas inlet and a water inlet in one of said members; a gas outlet and a water outlet in the other of said members, said inlets and outlets being arranged eccentrically with respect to said pivot; and a baffle plate attached to each member so arranged as to overlap that of the other member.

5. A muffler of the class described consisting of two members of substantially like structure having a centrally disposed pivot about which either of said members may be angularly adjusted and which normally constitutes a fastening means for said members; a gas inlet and a water inlet in one of said members; a gas outlet and a water outlet in the other of said members, said inlets and outlets being eccentrically arranged with respect to said pivot; a baffle plate attached to each of said members so arranged as to overlap that of the other member; and relief ports in each of said baffle plates.

6. A muffler of the class described consisting of two members of substantially like structure having a centrally disposed pivot about which either of said members may be angularly adjusted and which normally constitutes a fastening means for said members; a gas inlet in one of said members eccentrically arranged with respect to said pivot; a gas outlet in the other of said members also eccentrically arranged with respect to said pivot; and a baffle plate having converging walls attached to each of said members.

75 THOMAS E. GENTHNER.
ADELBERT L. STEVENS.
